TUNING FORK TYPE OSCILLATORS
Harry Reifel, Waltham, Mass., assignor to Stevens-
Arnold Inc., South Boston, Mass.
Filed Jan 10, 1961, Ser. No. 31,873
1 Claim. (Cl. 34—409)

This invention relates to tuning fork type oscillators, has as objects to simplify, and to reduce the costs of such oscillators.

Tuning fork type oscillators usually have a pair of reeds of magnetic spring metal, connected together at corresponding ends. One reed is usually vibrated by an electromagnet acting as a motor, which is supplied with A.C. by an oscillator, and vibrates the other reed in tuning fork action. Another electromagnet acting as a generator has voltages induced in it by vibration of the other reed, which are regeneratively fed back to the oscillator circuit, and are supplied to the load as take-off voltages. The reeds should be resonant at the applied A.C. frequency.

This invention simplifies the construction of, and the mounting of such reeds by forming a pair of such reeds and their interconnection in one piece, the interconnection being formed as a flat strip with the reeds at its center, and having ends extending substantially beyond the reeds. The reeds are attached to their associated oscillator frame by screws extending through the ends of the strap. The reeds need not be so precisely formed as formerly required since their nodal point will shift along their interconnecting strap when the two reeds do not have exactly the same lengths, until their lengths are effectively the same.

This invention will now be described with reference to the annexed drawings, of which:

FIG. 1 is a top plan view of an oscillator embodying this invention;

FIG. 2 is a section along the lines 2—2 of FIG. 1;

FIG. 3 is a projected view of the pair of reeds used, and

FIG. 4 is a circuit schematic showing the electromagnets of the oscillator connected in a transistor-driven oscillator circuit.

A base 10 of electric insulation has attached to its top, along opposite sides thereof, a pair of generally U-shaped brackets 11 and 12 to which are attached by screws 13 and 14 respectively, a pair of side plates 15 and 16 respectively, of magnetic metal. The brackets 11 and 12 have their legs formed as lugs 17 and 18 respectively, which contain tapped openings 19 and 20 respectively, for receiving screws which are not shown, for attaching a housing which is not shown.

Spacers 21 with the lower end of a magnetic shield 22 therebetween, are clamped between the brackets 11 and 12. A pair of spacers 23 and 24 extend between opposite ends of the tops of the plates 15 and 16, and are attached to the plates 15 and 16 by the screws 25 and 26 respectively.

Interconnecting strap 27 of reeds 28 and 29 extends across the spacers 23 and 24 at their centers, and is attached at its ends to the spacers 23 and 24 by screws 30 and 31 respectively. The strap 27 and the reeds 28 and 29 are formed in one piece from magnetic spring metal. The ends of the strap 27 which are attached to the spacers 23 and 24, extend substantial distances from the reeds 28 and 29 so that the portion of the strap 27 which extends between the reeds is floating.

The magnetic shield 22 extends midway between the reeds 28 and 29, and is attached at its upper end by spacers 33 and screws 34 and 35 to the side plate 15.

A pair of permanent magnets 38 and 39 are attached to the inner sides of the upper portion of the side plates 15 and 16 respectively, opposite the upper ends of the

2

reeds 28 and 29 respectively, and serve to magnetize the reeds.

An electromagnet 40 is attached to the inner side of the plate 15 by a bolt 41, opposite the outer side of the lower portion of the reed 28, and has a pole-piece 42 adjacent to the reed 28. A similar electromagnet 44 is attached to the inner side of the side plate 16 by a bolt 45, opposite the outer side of the lower portion of the reed 29, and has a pole-piece 46 adjacent to the reed 29.

10 There is a magnetic circuit through the magnet 38, the reed 28, the pole-piece 42, the side plate 15 and back to the magnet 38. There is a similar magnetic circuit from the magnet 39, through the reed 29, the pole-piece 46, and the side plate 16 back to the magnet 39. The shield 22 prevents the field of the electromagnet 40 from directly affecting the reed 29, and prevents the field of the electromagnet 44 from directly affecting the reed 28.

The base 10 has a socket guide 50, and socket prongs 51 for connecting the components of the oscillator to 20 external circuits.

As shown by FIG. 4, one end of the electromagnet 40 would be connected to the collector electrode of a transistor 54, with its other end connected to the negative terminal of a battery which is not shown. One end of the electromagnet 44 would be connected to the base electrode of the transistor, with its other end connected to the junction of resistors 55 and 56 which are connected in series across the battery. The emitter of the transistor is connected in series with variable resistor 57 to the positive terminal of the battery. The signal currents would be taken from across the electromagnet 44 by the output connections 58 and 59.

The electromagnet 40 is a motor which vibrates the reed 28, and the electromagnet 44 is a generator in which currents are induced by vibration of the reed 29. When the circuit shown by FIG. 4 is completed by connection to a battery, it is shock excited into oscillation, the A.C. oscillatory currents being fed through the electromagnet 40 for vibrating the reed 28. The attraction between the reed 28 and the pole-piece 42 of the electromagnet 40 would either be increased or decreased depending upon the instantaneous polarity of the applied A.C. voltage, causing the reed 28 to vibrate at the applied frequency to which it should be resonant. The reed 29 would be vibrated by the vibrations of the reed 28 applied to it through the interconnecting strap 27. The currents induced in the electromagnet 44 by the vibration of the reed 29, would be regeneratively fed back to the input of the transistor for maintaining the circuit of the latter in oscillation, and would be taken off through the connections 58 and 59 for supply to the load. A vacuum tube could be used instead of the transistor.

The strap 27 through being supported at its ends and not where it connects the reeds, permits, when the two 55 reeds do not have precisely the same resonant frequency as by one reed being slightly longer than the other, the nodal point to be displaced from the center of the portion of the strap which connects the reeds, to one side of the center sufficiently to cause the effective lengths of the 60 reeds to be the same.

What is claimed is:

A tuning fork type oscillator comprising a base of electric insulation, a pair of aligned, parallel, spaced-apart plates of magnetic metal attached at corresponding ends 65 to said base, a pair of spaced-apart, aligned, parallel spacers extending between and attached to the other ends of said plates, a strap of spring metal extending over and connected at its ends to said spacers, a pair of aligned, spaced-apart, parallel reeds of magnetic spring metal having corresponding ends connected to the central portion of said strap between said ends of said strap, an electromagnet for vibrating one of said reeds attached to the

inner side of one of said plates adjacent to the free end of said one reed, a second electromagnet in which currents are induced by the vibrations of the other of said reeds attached to the inner side of the other of said plates adjacent to the free end of said other reed, a shield sheet of magnetic metal attached to one of said plates and extending midway between said reeds parallel thereto, a permanent magnet for magnetizing said one reed attached to said one plate and having an end adjacent to the other end of said one reed, and another permanent magnet for

magnetizing said other reed attached to said other plate and having an end adjacent to the other end of said other reed.
